UNITED STATES PATENT OFFICE

ALFRED E. NORRIS, OF WESTFIELD, NEW JERSEY, ASSIGNOR TO THE REGIMA CORPORATION, OF RAHWAY, NEW JERSEY, A CORPORATION OF NEW JERSEY

FLOOR MACHINE

Application filed September 26, 1930. Serial No. 484,501.

My invention relates to floor machines of the type actuated by an electric motor and having a plurality of brushes mounted in a casing housing the motor and provided with a waxing unit as an attachment thereto.

An object of the invention is to provide an improved shaft for the brushes and an improved type of bearing supporting such brush shafts.

A further object of the invention is to provide an improved construction of waxing unit for use in connection with such floor machine and an improved method of attaching such unit to such machine, whereby my improved waxing unit may be removably secured to the floor polishing machine, such waxing unit being so constructed as to deliver to the floor, in advance of the brushes the proper amount of wax to be spread by the brushes, whereby an equal and uniform distribution of the wax over the floor to be polished is obtained.

A still further object of the invention is to provide the brushes of my improved floor machine with pads of felt suitable for buffing the waxed floor, such pads being removably secured to said brushes in a novel manner.

An embodiment of my invention is illustrated in the accompanying drawings in which:

Fig. 1 is a top plan view of the casing of my floor polishing machine with the waxing unit mounted in front of said casing;

Fig. 2 is a vertical cross-sectional view of the apparatus showing the manner of attachment of the yoke of the handle thereto;

Fig. 3 is a side elevation of my apparatus showing the waxing unit mounted in front of the casing;

Fig. 4 is a front elevation of the waxing unit;

Fig. 5 is a view of the novel felt buffing pad adapted to be secured to the brush of the floor machine, and

Fig. 6 is a vertical sectional view of one of the brushes showing the method of attaching the buffering pad thereto.

My floor polishing machine comprises a casing 1, preferably composed of two parts, 2 and 3, provided with a telescoped joint 4,

offset slightly from the median line of the machine, the two parts being rigidly secured together in any suitable manner. The casing 1 is provided with an enlarged chamber 5 in which is housed electric motor 6. On each side of the enlarged chamber 5 are two cylindrical chambers 7-7, the vertical axes of which are parallel to each other. The casing 1 supports the bearings for the motor shaft 8, mounted in bushings 9-9, of any suitable material, being cut away on one side adjacent the vertical chambers 7-7 to permit the worm gears 10-10 mounted on the upper ends of the brush shafts 11-11, to mesh with the right and left hand worms 12 and 12' with which said motor shaft 8 is provided and through which the rotary motion of shaft 8 is transferred to the brush shafts 11-11 to drive them in opposite directions. The casing 1 is preferably provided with two cover plates 13-13, each fitting over the vertical cylindrical chambers 7-7, forming a closure therefor.

Each worm gear 10 is preferably keyed to the upper end of a brush shaft 11 by a key 14 and is permanently retained thereon by a nut 15. Each brush shaft 11-11 is provided with a thrust or bearing collar 11' and is preferably mounted to turn in a bearing 16 forced into and permanently retained in the lower portion of a cylindrical chamber 7. The bearing 16 is a full bearing extending throughout the length of the space between the lower end of the shaft 11, i. e. from the thrust collar 11', and the worm gear portion 85 of the chamber 7 as I have found that such a full bearing gives a more rigid and durable structure and may be more easily assembled than the divided or aligned bearings of the prior art. Beside the marked advantage of my new type of construction in providing a greater bearing surface, with resulting increased structural strength, my improved bearing structure obviates the difficulty heretofore experienced in pressing a double bearing into a position which it should retain during the operation of the apparatus.

There being no substantial support against the side walls when the two portions of a divided bearing are inserted from the top and 100

bottom, any extraordinary pressure of the machine upon the floor to be polished, or even a slight bumping of the machine over the surface, would force the lower of the bearings upward, causing the brush shaft to lift upwardly, thereby raising the worm wheel and preventing a proper meshing of such wheel with the worm gear. The worm, accurately centered originally, thus rapidly wears away, and a noisy and inefficient operation of the apparatus results. With my unitary bearing, which may be further supported in a fixed position against the wall of the bearing chamber by set screw 16', these disadvantages are eliminated.

Each of the brush shafts 11 is provided with a helical groove 17 having an upward turn. This helical or spiral groove, being inclined in a direction opposite to that of the direction of rotation of the brushes, serves to prevent oil or grease leaking from the upper portion of the cylindrical chamber 7 in which the worm gear is housed, through the bearing chamber, downwardly through the brushes onto the floor. The dripping of oil from the machine is thus effectively eliminated, the spiral groove on the brush shafts serving to pump oil back into the worm gear chamber and at the same time providing adequate lubrication for the brush shafts.

Mounted on the brush body is a flanged hub 18, through which may be passed a screw 19 for supporting the brush body 20, having embedded therein a plurality of bunches of bristles 21 and supporting the weight of the machine upon the floor. The manner of attachment of the brush to the shafts 11—11 illustrated in the drawings is not original with me and I make no claim with respect thereto. It is pointed out, however, that by means of the metal loop 22, with which each of the brushes is provided, being rigidly secured thereto by bolts 23, 23, such brushes may be removed from the apparatus by the simple operation of inverting the housing, inserting a finger through the loop 22 and drawing the brush off from the end of the shaft by exerting a jerk on the loop.

The metal loops 22, which may be otherwise described as finger grips, are each provided with a female part 22 of a snap fastener adapted to receive one of the male parts 23' of a snap fastener, such male parts being mounted at the centers of opposite faces of a circular pad 24'. The pad 24' is of a size approximately that of the horizontal surface area covered by the brush bristles, so that when the pad is secured to the finger-grip of the brush by means of the cooperating portions of the snap fastener, it will substantially cover the surface of such bristles.

When the operation of waxing the floor with my apparatus has been completed, buffing of the waxed floor by means of the felt pads may then be accomplished by attach-

ing the pads to the brushes by the simple operation of snapping the male members of the fastener structure into the female members, thereby automatically centralizing the felt pads over the brush surface. The fact that the bristles of the brush are distributed in an annular area about the center of the brush, the pad being secured to the finger grip in the space within such annular area, leaves only that portion of the pad upon which the bristles exert a downward pressure, in contact with the surface to be buffed, so that the freedom of rotation of the brushes is not interfered with and the exposed male portion of the snap fastener is well above the surface of the floor. It is to be noted that if a circular pad of buffing material were merely placed against the bristles of the brush, great care would have to be exercised to have such pad exactly centered as the rotation of the brushes in such close proximity to each other in opposite directions would soon result in an interference of the two pads with each other's rotation and necessitate the stopping of the machine and a readjustment of the pads. With my novel structure and means of attaching the pads to the brush, the pads retain their proper positions below the respective brushes and perform their buffing functions without interference with each other and without possibility of working loose.

A further advantage of my structure is that a particular pad, after one of its sides has been used for buffing, may be easily disengaged from its position and reversed to present its opposite side to the floor to be buffed. This reversal of the buffing face of the pad is accomplished by the simple operation of pulling on the pad to disengage the engaged male portion 23' of the snap fastener from the female portion 22', reversing the pad, and engaging the second male portion of the fastener with said female portion. A slight pressure on the exposed male portion will accomplish this result after the pad has been centered on the brush.

Within the chamber 5 and rigidly mounted on the motor shaft 8 may be provided a fan 24 drawing air into the motor chamber for cooling such motor.

The casing 1 is also preferably provided with a yoke 25 which is pivotally secured to opposite sides of the casing at the ends of the yoke by screws 26—26. At one end of one of the cover plates 13 is preferably provided a stud 27 having a slight depression in its upper surface adapted to be engaged by a spring pressed plunger 28 housed within a projection 28' of the yoke 25, when the yoke is in substantially vertical position, to hold the handle of the apparatus in a vertical position when the machine is not in use. The usual cable 29 and electrical plug 30 connect the motor 6 to the handle 31.

The waxing unit designed for use with my improved floor machine comprises a cylindrical wax container or reservoir 32 having a cylindrical neck 33 at its lower end and a cover 34 provided with a bayonet type of lock 35 to prevent the cover 34 from being disengaged from the top of the reservoir when the waxing unit is overturned, thus preventing the flowing out of the waxing material therefrom in case of accidental overturning of the unit or in case such unit is laid upon its side after being removed from the casing. In order to provide a further safeguard against the accidental overturning of the waxing unit and to provide facility in filling the container with waxing material when disengaged from the casing of the apparatus, I provide such waxing unit with a support 36 in the form of a lug to keep it upright when detached from the machine.

The neck 33 of the waxing unit terminates in a cylindrical chamber fitting into the upper portion 37 of the carriage body 38. The lower portion of the carriage constitutes a housing within which are mounted two small intermeshing spur gears 39 and 40. The forward gear 39 is rigidly keyed to a shaft 41 mounted to rotate in aligned bearings 42-43. On the ends of the shaft 41 are wheels 44-45 of the carriage rigidly secured to the shaft in any suitable manner. The wheels 44-45 are preferably provided with rubber tires to provide sufficient friction to secure their rotation on the polished floor. The above described carriage and gear arrangement, comprising a mechanically operated pump for delivering wax from the reservoir to the floor, is not original with me and I make no claim with respect thereto.

Immediately below the intermeshing portions of the teeth of the gears 39 and 40 is a small chamber in communication with a passageway extending vertically downwardly into which are fixedly secured two thin walled tubes 46-47 extending laterally from the center of the carriage at the lower end thereof and having their openings at a distance from the central point between the wheels of the carriage so that the wax issuing from such tubes is deposited at points to the side of the central line of the apparatus and in advance of the brushes. By providing such a duplex outlet for the wax instead of the single central outlet heretofore used, I overcome a marked disadvantage of apparatuses of this type heretofore employed. When a single centrally located aperture is used the waxing material issues from the container of the waxing unit at a point exactly midway between the brushes and when the apparatus is propelled forwardly, the rotating brushes fail to uniformly smear the waxing material over the surface to be waxed and in fact leave a distinct streak of undistributed wax along the line of travel of the apparatus. It is

therefore usually necessary to go over the same area repeatedly so as to eliminate the streak of wax left by the rotating brushes. Since the wax is being fed always midway between the centers of such revolving brushes, it is impossible to absolutely eradicate the streak of waxing material left upon the surface over which the apparatus has just been passed. By means of my novel construction of the outlet from the waxing unit utilizing two outlets, each extending laterally to a point at a distance from the central line of the apparatus, I make possible the absolutely even distribution of the wax over the floor to be polished, as such wax is fed in two streams, one each immediately in advance of a brush which distributes such wax over the area which it traverses.

Since it may be desirable to use my floor machine without the waxing unit, I provide a construction whereby such waxing unit may be easily detached from the casing of the floor machine. As shown in Fig. 3, the lower forward edge of the casing 1 has an enlarged portion 48 having two vertical recesses 49, 49 into which may be placed one of the leg portions of U-shaped supporting elements 50 rigidly mounted by means of their threaded leg portions and nuts 51 on a platform 52 provided on the carriage 38 of the waxing unit. By reason of this construction of detachably securing the waxing unit to the casing, a proper positioning of the waxing unit in advance of the brushes is assured at all times, the U-shaped elements 50 being capable of riding vertically within the recesses 49, 49 so that, irrespective of the pressure exerted upon the brushes by the operator of the apparatus, which may change the distance of the casing from the floor surface, the waxing unit will have its wheels frictionally engage the surface of the floor with a uniform pressure. The feeding of the wax by the mechanical gear pump which is dependent upon the frictional engagement of the floor surface by the wheels, will therefore be uniform irrespective of the force with which the apparatus is pressed against the floor and irrespective of the speed with which the apparatus is moved over the floor.

I claim:

1. In a floor polishing machine, the combination of a housing, a motor journalled on a shaft within said housing, a brush shaft journalled in said housing to rotate on a vertical axis, a brush at the end of said shaft and a waxing unit detachably secured to said housing by means including a pair of U-shaped elements rigidly connected to said waxing unit and having one of the leg portions of each of said pair of U-shaped elements positioned within a vertical recess in said housing, whereby said waxing unit is

freely movable vertically and independently of said housing.

2. In a floor polishing machine, the combination of a housing, a motor journalled on a shaft within said housing, a brush shaft journalled in said housing to rotate on a vertical axis, a brush at the end of said shaft and a waxing unit comprising a reservoir for wax and a carriage supporting said reservoir and having freely rotatable means mounted to roll on the floor and to support the weight of said unit on said floor, said waxing unit being provided with a passageway extending vertically downwardly within said waxing unit, a pair of tubes extending laterally and downwardly from the center of the carriage and having their openings at a distance from the central point between the wheels of said carriage so that the wax issuing from such tubes is deposited at points to the side of the central line of the apparatus and in advance of the brushes.

3. A waxing unit for use with a floor polishing machine, comprising a reservoir for wax, a carriage supporting said reservoir and having freely rotatable means mounted to roll on the floor and to support the weight of said unit on said floor, said waxing unit being provided with a passageway extending vertically downwardly within said unit, a pair of tubes extending laterally and downwardly from the center of the carriage and having their openings at a distance from the central point between said freely rotatable means so that the wax issuing from such tubes is deposited at points to the side of the central line of the waxing unit, and means for detachably securing the waxing unit to the floor polishing machine with which it is to be used, including a pair of U-shaped elements rigidly connected to said waxing unit and having one of the leg portions of each of said pair of U-shaped elements vertically disposed and depending in substantially parallel relationship with such carriage, whereby said waxing unit is freely movable vertically and independently of the floor polishing machine with which it is adapted to be used.

50 4. A waxing unit comprising a reservoir for wax and a carriage supporting said reservoir and having freely rotatable wheels mounted to roll on the floor and to support the weight of said unit on said floor, said waxing unit being provided with a passageway extending vertically downwardly within said waxing unit, a pair of tubes extending laterally and downwardly from the center of the carriage and having their openings at a distance from the central point between the wheels of said carriage so that the wax issuing from such tubes is deposited at points to the side of the central line of the waxing unit.

ALFRED E. NORRIS.
